Peter Bendmann,
By *Macay (M. A. J.)* Atty.

UNITED STATES PATENT OFFICE.

PETER BENDMANN, OF FRANKFORT-ON-THE-MAIN, GERMANY.

ELECTRIC ARRESTER.

1,413,093.

Specification of Letters Patent. Patented Apr. 18, 1922.

Application filed April 1, 1921. Serial No. 457,778.

To all whom it may concern:

Be it known that I, PETER BENDMANN, a German subject, and resident of Frankfort-on-the-Main, Germany, have invented new and useful Improvements in Electric Arresters, (for which I have filed application in Germany August 9, 1919, No. 390,329,) of which the following is a specification.

Excess voltage arresters are known that comprise a spark gap, which can be short circuited by a magnetically controlled switch for the purpose of discharging the excess voltage to earth. These excess voltage arresters have hitherto only been used for direct current or for single phase alternating current. The present invention relates to an excess voltage arrester for polyphase alternating currents. It is so arranged that all the phases are simultaneously shunted when one or more phases operate so that all phases are earthed and are also simultaneously short circuited with one another. The shunting and short circuiting is effected by means of a single electro-magnetically controlled switch, which, after discharging the excess voltage, automatically again disconnects the earthed lead. The apparatus is so arranged that there is a resistance behind the spark gap and the winding of the electromagnet of the switch is connected in parallel with this resistance. This arrangement enables all excess voltages exceeding about 10% of the normal to be discharged with reliability. The apparatus operates so quickly that the arc at the discharge point cannot cause any damage to the insulators, etc.

The accompanying drawing shows diagrammatically by way of example such an excess voltage switch. A transformer *a* is connected to a line *b* comprising three wires corresponding to three phases. Branched off from this line are the three spark gaps *c*, behind which, over a common resistance *d*, a conductor *e* is connected to earth. The resistance *d* is short circuited by the coil *f* of the electromagnet, which operates a switch *h* pivoted at *g*. Branch conductors *i* lead from spark gaps *c* to the contacts of this switch.

In front of these branch conductors *i* there are resistances *k* inserted in the individual conductors.

On the occurrence of an excess voltage in any of the phases, there is a spark discharge at the corresponding spark gap *c*. Since resistance *d* is greater than coil *f*, the greater part of the capacity current or the supply

current following the spark discharge goes through this coil *f*, which is thereby energized and pulls up the switch arm *h*. Thereby all the spark gaps are connected to the earthed lead *e* and are short circuited with one another. Hence the discharge arc at the spark gap is extinguished and no more current passes through the coil *f*; thus the switch *h* is released and disconnects the earth conductor from the branch leads *i*. Preferably, an oil immersed switch should be used.

The apparatus operates in a very similar manner during momentary earthing of the overhead line or when one of its insulators breaks down. Thereby one phase is connected to earth and an excess voltage occurs at the spark gaps of the other phases of the excess voltage arrester so that these cause the apparatus to operate.

The current in the arc at the overhead line can now flow away over the excess voltage arrester since its resistance is less than that of the arc, thereby the disturbance is removed and the contact is again opened.

Now what I claim and desire to secure by Letters Patent is the following:

1. In excess voltage arresters for polyphase alternating current lines, a permanently maintained spark gap for each phase, a switch for grounding said gaps and electro-magnet mechanism for closing said switch when current passes any one of said gaps, said switch automatically returning to normal position upon the cessation of current through said mechanism.

2. In an excess voltage arrester for polyphase alternating currents, comprising spark gaps on each phase a switch to short circuit phases, a resistance, said switch in parallel with said grounded resistance.

3. In an excess voltage arrester for polyphase alternating currents, comprising a branch from each phase conductor, having a permanently maintained spark gap, a ground connection for said branches, a switch, an operating coil for said switch between the gaps and ground and a resistance in parallel with coil, said grounded switch automatically short circuiting said branches upon the passage of current across a gap and automatically returning to normal position upon cessation of current across the gaps.

4. In an excess voltage arrester for polyphase alternating currents, comprising a branch from each phase conductor having a

ground connection common thereto, a spark gap in each branch and a resistance between each spark gap and the phase conductor, a switch point connected to each branch between the spark gap and resistance, a switch common to all of said points, a resistance in said ground connection and a switch operating solenoid in parallel with said last named resistance, whereby said grounded switch short circuits and grounds said branches

when current passes said gaps and is automatically opened when said solenoid is de-energized.

In testimony that I claim the foregoing as my invention, I have signed my name this 15
31st day of Janr., 1921.

PETER BENDMANN.
